MACHINE FOR PLANING AND JOINTING

John C. Ryan, Toronto, Ontario, Canada

Application October 31, 1947, Serial No. 783,384

3 Claims. (Cl. 144—3)

1

The object of the invention is to plane and joint woods of various kinds, with or against the grain, to give the work a smooth finish and so dispense with any further processing thereof, such as sandpapering, now necessary where wood, used in cabinet making, for example, is planed and jointed by machines of this class now on the market.

Other objects of the invention are:

(1) To design a machine that can be used to give a fine finish to pieces of wood of a very wide range in size. For example: small pieces of wood one inch long by one eighth of an inch square can be as easily given a smooth finish, sides and ends, as can pieces of wood four feet long by five inches square, thus making it possible to utilize pieces of wood that otherwise, in wood-working shops, is waste material.

(2) To control the path of movement of the cutters so that they will not at any time contact the work after they have functioned thus avoiding any possibility of displacing the processing work and mar the finished surface thereof.

(3) To give the pairs of cutters the required clearance with the front edge of the table to insure that the work will be cut straight and true with or against the grain.

(4) To so mount the table that it may have a pivotal movement around its extreme forward edge, which edge lies parallel to and in the same vertical plane as the fixed bench, thereby making it possible to cut the size of the work at various angles, and without the work being interfered with by the mounting means for the table as it is fed to the cutters.

(5) To provide a particular type of bearing support for the table at each side thereof so that its axis of movement will pass through the axes of said supports which latter are so constructed as not to interfere with the passage of the work to and from the cutters.

(6) To provide means whereby the journalling means for the table at each end may be constantly held to have a fixed axis of movement, irrespective of the arc of said journalling means may be moved through thereby insuring a fixed axis for the table.

(7) To provide particular means whereby the angular position of the table may be determined and fixed.

(8) To remove from the work any stringy or chipped portions remaining at the edges of certain classes of wood after the cutters have functioned.

(9) To provide a specific type of open bearing for the table, and

(10) To provide a balanced cutter head set at an angle to the front edge of the table so that a section of the fixed bench may be partly housed therein to provide a guard for the cutters and to allow these latter a working range of 90° and at the same time act as a guide for the advancing work.

2

Various other objects of the invention will be referred to later in the specification.

The invention basically consists of a method for coordinating the three following movements: (1) the continuous feeding of the work in a given direction; (2) the consecutive moving of the pairs of cutters around a fixed axis of rotation angularly towards the work laterally thereof with their cutting edges parallel to the direction of movement of the work to bring them to the work to function, and (3) the consecutive moving of said cutters angularly away from the work immediately after they have functioned.

The invention further consists in the manner of mounting and conditioning the cutters to carry out the method, and the article made by this method.

The invention broadly consists of a cutter-head angularly positioned with relation to the table supporting the work, the said cutter-head supporting a plurality of pairs of cutters, located at different radii from the axis of rotation of said cutter-head, with their cutting edges parallel to the direction of movement of the work, so that as they are carried through a given path by movement of said cutter-head they will be brought laterally into contact with the work and function, and after functioning will be moved away from the work, so thereby accomplishing the result sought, as hereinafter more particularly explained.

In its preferred form herein described and illustrated in the accompanying drawings the table is pivotally supported.

35 Fig. 1 is a front elevation of the machine.

Fig. 2 is a rear elevation of the machine.

Fig. 3 is a plan view of the machine.

Fig. 4 is an elevation of one end of the machine on an enlarged scale.

40 Fig. 5 is a perspective view of the particular bearing means for the table, and the means to determine the angle at which the table is set.

Fig. 6 is a plan view of portion of the table showing the relative position of a pair of cutters when functioning, which cutters are shown as supported by portion of the cutter-head. This view also shows the trimming knife supported by a guide member for the work.

Fig. 7 is a face view of portion of the cutter-head showing how the finishing cutters overlap portion of the path of movement of the rough cutters.

50 Fig. 8 is a longitudinal section on the line 8—8, Fig. 4.

Fig. 9 is a plan view of portion of the cutter-head showing a pair of cutters supported thereby to illustrate the different distances these cutters project beyond the cutter-head.

Fig. 10 is a vertical section, on a reduced scale on the line 10—10, Fig. 1.

60 Fig. 11 is a horizontal section on the line 11—11, Fig. 1, and

Fig. 12 is a vertical section on the line 12—12, Fig. 1.

In the drawings like characters of reference refer to the same parts.

The cutters are in pairs, and there are two types of cutters in each pair—the rough cutters *a*, and the finishing cutters *b*. The rough cutter of each pair is located at the same radius from the axis of rotation of the cutter head 46, which is located above the table of the machine, and the finishing cutter *b*, of each pair is located at a shorter radius from this axis. Each finishing cutter projects a very short distance in advance of its fellow rough cutter. The result is the rough cutters first contact the work, and the path of movement of each rough cutter is overlapped in part by the path of movement of its finishing fellow-cutter to ensure the proper finishing of the work (Figs. 6 and 7). In the machine in use the cutters are three-eighths of an inch square, though the shape of the cutters may vary.

The fixed base 2 of the machine is supported by any suitable means such as the braced legs shown, and carried by this brace by suitable means such as the supports 4, is a rear fixed horizontal table 3. Attached to the fixed table 3, are end plates 5 and 5'', and the knee 5', which brace the fixed bench 6. This bench is supported by the fixed table 3, which in turn is further supported by the plates 7. There is nothing novel in this construction.

The movable bench 8 is supported by any suitable means, and its function is to regulate the depth of cut to be made in the work 0. As shown (Figs. 2 and 3), the bench is supported and guided by rods 9, suitably held in the brackets 10, supported by the table 3, and braced by the knees 11. A hand wheel 12, is carried by a rod 13, held in a support 13', coupled to the bench 8. This rod passes through a bracket 14, carried by the base 2, and table 3, and has threaded engagement with the bracket 15, carried by the bench 8. By the described or other suitable means, the bench 8 is moved transversely of the machine. There is nothing patentably new in this construction.

Supported by the walls 7, at its base 16 offset therefrom is a guide-member 17, which functionally is a section of the fixed bench 6. The face of the member 17 is in the same vertical plane as the face of the bench 6.

The table 18 supports the work 0 undergoing processing and it is suitably supported to have a fixed pivotal movement on its extreme forward edge 19, which lies parallel to and in the same plane as the face of the bench 6, and guide-member 17.

The means used to pivotally mount the table 18, must not interfere with the movement of the work to and from the cutters, and must maintain the extreme front edge 19, of the table, in all angular positions, in a fixed pivotal position. The preferred form of means to pivotally mount the table 18, comprises, at each side thereof, 2 segmental bearing-members, thus providing unobstructed passage of the work to and from the machine. At each end of the table 18, is fastened a guide-arm 20, the rear portion of each of which is wider than the front portion 21. Between these 2 portions is countersunk a segmental bearing-member 22, the open side of which is uppermost. A segmental socket 23 supports each bearing-member 22. These sockets 23 are countersunk in a semi-circular plate 24, supported at each side of the table by the end plates 5, and 5'', carried by the table 3.

As shown clearly in Figs. 4 and 5, the extreme forward edge 19, of the table 18, is in alignment with the axes of the segmental bearing-member 22, and segmental sockets 23. The sockets 23, give ample support to the bearing-members 22, and it will be noticed these sockets and bearing-members can not in any way interfere with the passage of the work thereover. They will definitely support the edge 19, of the table 18, in a fixed axial position.

Around the perimeter of each plate 24, is secured a metal facing 25, which is concentric with the sockets 22 and 23. In sliding contact with the facing 25, is a shoe 26 (Fig. 8), carried by a follower 27, held in a slot 28, formed in each arm-portion 21. Carried by each arm-portion 21, is a dowel pin 29, which passes through a dowel slot 30, formed in each follower. A pocket 31 is formed longitudinally in each follower 27, and extended into the outer end of each arm-portion 21, in each is housed a spiral-spring 32. The function of these springs is to maintain the shoes 26, constantly in contact with the metal facings 25, and hence each segmental bearing-member 22, is definitely held in contact with its associated segmental socket 23.

At the right-hand of the machine a plate 24 is located. This plate is marked with a scale 30 to show the angles through which the table 18 may be moved. Co-acting with this scale is a pointer 33, carried by its associated arm portion 21.

Any suitable means may be used to adjust 35 the angular position of the table 18, and hold it securely in that position. The preferred means for this purpose consists of a pair of toothed racks 34, hinged to the underside of the table 18, near the outer side thereof (Fig. 4). These racks operate through slots 35, in the base 2, and are held in mesh with the pinions 36, keyed to a shaft 37 mounted in suitable bearings depending from the base 2 (Figs. 1 and 2). Also mounted on the shaft 37, are yoke-bearings 38, which embrace each pinion 36, and 45 also each rack (Figs. 11 and 12). In order to keep the pinions and racks constantly in mesh and the yoke-bearings fully in contact with the racks each yoke-bearing 38 is provided with a shoe-plate 39, through each of which is threaded a screw 40, partly tapped into each yoke-bearing. Mounted on each screw is a spiral-spring 41, by means of which the desired pressure may be maintained.

55 A hand-wheel 42 is keyed to the shaft 37, and also keyed to said shaft is an index wheel 43, peripherally provided with a number of spaced slits radially disposed with relation to the axis of the shaft 37.

60 By means of the devices just described the table 18 may be placed in the desired angular position. Fastened to the fixed table 3 is a support 44, to which is pivoted a keeper 45. By placing this keeper in one of the slits the 65 table may be securely held in the desired angular position.

The front edge of the table 18 is provided with a metal plate, and it is the edge 19 of this plate that is the axis of the table. This plate is cut away at 49 (Figs. 3 and 6) for a distance of approximately five-eighths of an inch in length to a depth of fifteen-thousandths of an inch to form a gap in which the finishing cutters work.

70 After the cutters have been mounted in the cutter-head 46, this latter, by means of its shaft

47, is angularly mounted in any suitable bearings supported by the table 3, in position so that its face 48 will operate at an acute angle to the front edge 19, of the table 18, in order to give the pairs of cutters clearance with the work after functioning, and with any part of the machine at any time. The cutting ends of the cutters are now ground to make them parallel to this front edge 19. When correctly finished the face of the rough cutters *a* is in the same plane as the edge 19, and the face of the finishing cutters is a very short distance behind the said edge 19, of the faces of the aligned co-acting members 17 and 6. In a machine in use the cutters *b* have a clearance with the machine on their up-movement of one-sixteenth of an inch.

The finishing cutters *b*, project one inch plus .005, and the rough cutters *a* project one inch beyond the face 48, of the cutter-head 46 (Fig. 9).

The angle at which the cutters are held to operate in by the cutter-head together with the position of the cutting ends of these cutters with relation to the table 18 (Fig. 6) and to each other will insure a flat and even finish of the work. Care must be taken to keep this angle to the table 18 as small as possible to thereby avoid "dishing" of the finished surface of the work.

In Fig. 6, the work is shown as held against the bench 8, while moved in the direction indicated by arrow. Presently the cutters *a* and *b* start to function in this order. Almost immediately after the cutters have started to cut the work will be brought into contact with the guide-member 17, and presently will pass on into contact with the face of the bench 6.

If the forward end of the work 0 is not laterally supported after it leaves the bench 8 it will be apparent to one skilled in the art that the work could not be kept in a given line of forward movement with the result the work would not be properly finished.

The trimming knife or blade *c*, is countersunk flush with the outer face of the guide-member 17. The cutting edge of this blade is segmental in form with a radius struck from the axis of the shafts 41, and it projects about one-eighth of an inch beyond the perimeter of the member 17. As shown in Fig. 1, the said cutting edge extends above and below the front edge of the table 18. The function of this cutting edge is to remove tag ends and chipped parts of wood undergoing process. This blade *c* is provided with a recess *d* (Fig. 6), to permit passage therethrough of any material severed by the knife which passes by the edge of the knife.

As shown in Fig. 10, the waste material passes into any suitable chute *e*. This figure also shows the cutter-head as counterbored thereby permitting the member 17 to be partly housed therein with its outer surface in the same vertical plane as the bench 6.

Fig. 7 shows clearly that the path of movement of the rough cutters *a* is partly overlapped by the finishing cutters *b*.

The guide-member 17, is spaced apart from the benches 6 and 8. This construction permits ready access to the cutters *a* and *b*, and facilitates acute angular positioning of the cutter-head 46, with respect to the edge 19, of the table 18.

While herein has been illustrated and described specifically the preferred form of construction for carrying out the objects of this invention, it must be understood that the illustrated embodiment

ment of the invention is not to be considered as narrowing the scope of the claims. For instance, the table 18 may be fixed as disclosed in my application No. 695,743, filed September 9, 1946 (now abandoned), for some classes of users.

I claim:

1. A machine of the class described comprising a table provided with a gap in its front edge; a cutter-head; a rotatable shaft journalled at an acute angle to said front edge on which said cutter-head is secured with its axis of rotation above said table; a plurality of pairs of rough and finishing cutters held in said head with their cutting ends ground parallel to the said front edge, the finishing cutter of each pair functioning in said gap when making its cut; a gauge adjoining and parallel to the front edge of said table to regulate the depth of cut made in the work; fixed means to maintain the desired path of movement of the work while it is being processed comprising a bench adjoining and parallel to the front edge of said table, and a guide member carried by said fixed bench in alignment therewith and located immediately in front of said cutter-head.

2. A machine of the class described comprising a table provided with a gap in its front edge; a cutter-head; a rotatable shaft journalled at an acute angle to said front edge on which said cutter-head is secured with its axis of rotation above said table; a plurality of pairs of rough and finishing cutters held in said head with their cutting ends ground parallel to said front edge, the finishing cutter of each pair functioning in said gap when making its cut; a gauge adjoining and parallel to the front edge of said table to regulate the depth of cut made in the work; fixed means to maintain the desired path of movement of the work while it is being processed comprising a bench adjoining and parallel to the front edge of said table; a guide-member carried by said fixed bench in alignment therewith and located immediately in front of said cutter-head; means to pivotally mount said table for movement around its front edge, and means to adjust the angular position of said table.

3. A planer and jointer as set forth in claim 1, having a trimming knife firmly carried by said guide-member directly behind the functioning cutters.

JOHN C. RYAN.
